COMBINED MOUNT AND HANDLE FOR A PHONOGRAPH OR SIMILAR ARTICLE

Richard S. Hart, Wheaton, Ill., assignor to V-M Corporation, Benton Harbor, Mich., a corporation of Michigan

Filed June 6, 1966, Ser. No. 2,576

Term of patent 14 years

(Cl. D56—4)

FIG. 1 is a left side, front and top perspective view of a combined mount and handle for a phonograph or similar article, showing my new design;

FIG. 2 is a bottom plan view;

FIG. 3 is a rear elevational view; and

FIG. 4 is a right side elevational view, the opposite side being substantially a mirror image thereof.

The dominant features of my new design reside in the portions shown in full lines.

I claim:

The ornamental design for a combined mount and handle for a phonograph or similar article, substantially as shown and described.
